(57) **CLAIM**

The ornamental design for a molded tortilla pocket, as shown and described.

DESCRIPTION

FIG. 1 is a top, front perspective view of a molded tortilla pocket according to our new design;

FIG. 2 is a front elevational view of the molded tortilla pocket;

FIG. 3 is a rear elevational view of the molded tortilla pocket;

FIG. 4 is a left side view of the molded tortilla pocket;

FIG. 5 is a right-side view of the molded tortilla pocket;

FIG. 6 is a top plan view of the molded tortilla pocket; and, FIG. 7 is a bottom plan view of the molded tortilla pocket. The dash-dot-dash symbolic break lines shown in the middle portion of the molded tortilla pocket indicate that the appearance of any portion of the article between the break lines forms no part of the claimed design. The evenly-spaced broken lines illustrating the food inside of the molded tortilla pocket and the hand in FIG. 1 illustrates environment that form no part of the claimed design while the remaining evenly-spaced broken lines in the drawings illustrate portions of the molded tortilla pocket that form no part of the claimed design. The dash-dot-dash broken lines shown in FIGS. 1-7 illustrate the boundary of the claimed design which forms no part thereof.
